[57] ABSTRACT

An elongated slot is formed in the interior of a toy gun body and a relatively flat slide is movable within the slot. A recess is formed in one side of the slot, with yielding means such as an elastic band over the recess, and a marble positioned on top of the elastic band over the recess. A row of marble-engaging openings is formed in the flat slide, with each of the openings being smaller in diameter than the marble but large enough in diameter to permit a portion of the marble to project through the flat slide. A handle is attached to the flat slide and projects outside of the body in such a way that it can be grasped and pulled to move the marble-engaging openings over the marble. This causes the marble to snap into and out of the marble-engaging openings and produce a sequence of explosive sounds and vibrations simulating those of an automatic rifle or other weapon.

TOY GUN

BACKGROUND OF THE INVENTION

Many different approaches have been used in designing noise-making toys that simulate weapons, but, except for cap guns and the like, none of these approaches have succeeded in producing a noise that is sufficiently suggestive of a real weapon to satisfy children for very long. Accordingly one object of this invention is to provide a toy gun which makes a more realistic sound than heretofore found in the art and produces a mild kickback effect.

Another object of this invention is to provide a toy gun of the above-noted character which is simple in structure and reliable in operation.

A further object of this invention is to provide a toy gun of the above-noted character which utilizes readily available materials and is relatively inexpensive to manufacture.

SUMMARY OF THE INVENTION

In accordance with this invention, the above-noted objects are attained by using a marble, an elastic band, and a series of marble-engaging openings in a flat slide plate as the basic noise-making mechanism for a toy weapon. An elongated slot is formed in the interior of a toy gun body and a relatively flat slide is movable within the slot. A recess is formed in one side of the slot, with yielding means in the recess, and a marble positioned between the yielding means and slide. A row of marble-engaging openings is formed in the flat slide, with each of the openings being smaller in diameter than the marble but large enough in diameter to permit a portion of the marble to project through the flat slide. Means are provided for moving the flat slide back and forth, which causes the marble to snap into and out of the marble-engaging openings and produce a sequence of explosive sounds and vibrations simulating those of an automatic rifle or other weapon.

DESCRIPTION OF THE DRAWINGS

FIG. 1 is a partially cut away side view of one illustrative embodiment of the invention;

FIG. 2 is a plan view of the embodiment shown in FIG. 1;

FIG. 3 is a cross-sectional view taken on the line 3—3 of FIG. 1; and

FIG. 4 is a view similar to FIG. 3 showing a modification.

DETAILED DESCRIPTION OF THE INVENTION

Referring to the figures, one illustrative toy gun of this invention comprises a body 10 which is composed of two matching sides 12 and 14 which, in the illustrated embodiment, are shaped to resemble an automatic rifle or the like. The two sides 12 and 14 are preferably made of a suitable molded plastic and are attached to each other by any suitable means. An elongated slot 16 is formed in the interior of the portion 14 of the body 10, and a flat slide 18, preferably made of a relatively rigid and tough plastic material, is movable back and forth within the slot 16. The flat slide 18 has a handle 20 projecting from the lower edge thereof which serves as a handle for moving the slide between the two positions indicated by dashed lines which cor-

respond to abutment of the slide 18 against the two ends of slot 16. A recess 24 is formed in the body portion 14 in communication with a portion of the slot 16. An elastic band 26 is attached to the body member 14 over the recess 24 and a marble 28 is pressed into the recess 24 and held there by pressure from the side of slide 18. A row of marble-engaging openings 30, 32, 34, 36, and 38 is formed in the slide 18 and positioned to be in line with the marble 28. The marble-engaging openings 30-38 are smaller in diameter than the marble 28, but are large enough in diameter to permit a portion of the marble to project therethrough. In the position shown in the drawings, the elastic band develops a considerable force which constantly urges the marble to move toward the other side of the gun body. When the slide 18 is moved from the position shown in the drawing, the marble rides over the edge of the marble-engaging opening 34 and then as the slide moves forward drops into the next marble-engaging opening 32. The margin of each of the openings 30-38 which faces the marble is chamfered or rounded as at 40 in FIG. 3 so that an opening can be more readily moved into and out of engagement with the marble.

When the marble moves from one opening to the other, the force of the elastic band causes it to make a clicking noise when it leaves the one opening and a sharp, explosive noise when it enters the other opening thereby producing a combination of clicks and explosive sounds that simulate the noise of a real weapon as far as children are concerned. When the handle 20 is moved back and forth rapidly the resulting sound simulates the operation of a sub-machine gun or automatic rifle, and there is a simulated milk kickback effect. It should be mentioned that the noise produced by this invention does not sound like the explosion of a gun but rather that it makes a sound having a particular quality that realistically simulates the sound of a weapon in the context of children's play.

In the modification of FIG. 4, instead of having elastic the yielding means is a spring 50 within the recess 24. A cup-shaped member 51 is slideable in the recess and receives the upper end of the spring. The cup-shaped member may have a dished portion 52 to receive the lower portion in the marble. When the gun is operated the spring 50 performs the same function as the portion of the elastic band 26 which is over the recess in FIG. 3.

From the foregoing description it will be apparent that this invention provides a toy gun which makes a more realistic sound than heretofore known in the art, and which utilizes readily available material and is relatively inexpensive to manufacture. Although the invention has been illustrated by description of one concrete embodiment, it should be understood that the invention is by no means limited to the disclosed embodiment since many modifications can be made in the disclosed structure without altering the fundamental principles of operation. Also the novel features of the present invention may readily be embodied in other weapons than rifles or in other noise-making toys. Accordingly, this invention includes all modifications and uses as may fall within the scope of the following claims.

What I claim is:

1. A noise-making toy comprising a body with opposed sides, said body having an elongated slot formed therein between said sides, a relatively flat slide movable within said slot, there being a recess in one side of said body communicating with said slot on one side of said slide, yielding means associated with said recess, a marble having a portion positioned in said recess between said yielding means and said flat slide, and a row of marble-engaging openings formed in said slide and communicating with the side of the slide which is adjacent said marble, said marble-engaging openings being positioned to be moved in sequence across said marble when said flat slide is moved within said slot, thereby making an explosive noise.

2. A toy as defined in claim 1 wherein each of said marble-engaging openings extends completely through the slide and is smaller in diameter than said marble but

large enough in diameter to allow a portion of said marble to project therethrough.

3. A toy as defined in claim 1 wherein said body comprises two side members which are joined together along a plane.

4. A toy as defined in claim 3 wherein said slot is coplanar with the joint between the two sides of said body.

5. A toy as defined in claim 1 in which the yielding means is an elastic fabric band connected to the body over said recess and having a marble-engaging portion yielding projectible into the recess.

6. A toy as defined in claim 1 in which the recess in the toy body is deep enough to accommodate said marble as the marble snaps from one slide opening to another.
